(57) **CLAIM**

The ornamental design for a “non-spill paint cup,” as shown and described.

DESCRIPTION

FIG. 1 is a top front perspective view of a “non-spill paint cup” showing my new design;

FIG. 2 is a front elevational view thereof;

FIG. 3 is a top plan view thereof;

FIG. 4 is a right side elevational view, the left side being the mirror image thereof;

FIG. 5 is a rear elevational view thereof; and,

FIG. 6 is a bottom plan view.
